(57) **CLAIM**

The ornamental design for a display device for vehicle, as shown and described.

DESCRIPTION

FIG. 1 is a front, right, top perspective view of a display device for vehicle showing our new design in an alternate configuration of use;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right, top perspective view of the display device for vehicle showing our new design in an alternate configuration of use in which a jog dial is retracted;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, right, top perspective view of the display device for vehicle showing our new design in an alternate configuration of use in which the center of the retracted jog dial protrudes;

FIG. 16 is a front view thereof;

FIG. 17 is a rear view thereof;

FIG. 18 is a left side view thereof;

FIG. 19 is a right side view thereof;

FIG. 20 is a top plan view thereof; and,

FIG. 21 is a bottom plan view thereof.

The evenly spaced broken line showing in the figures is for the purpose of illustrating portions of the display device for vehicle that form no part of the claimed design. The dash-dot-dot broken line represents environmental subject matter only and forms no part of the claimed design.
